DESIGN FOR A COMBINED BOTTLE AND STOPPER

Bernard B. Klebanoff, Philadelphia, Pa.

Application October 2, 1946, Serial No. 133,689

Term of patent 7 years

(Cl. D58—6)

To all whom it may concern:

Be it known that I, Bernard B. Klebanoff, a citizen of the United States, residing at Philadelphia, Pennsylvania, have invented a new, original, and ornamental Design for a Combined Bottle and Stopper, of which the following is a specification, reference being had to the accompanying drawing, forming a part thereof.

In the accompanying drawing:

I claim:

The ornamental design for a combined bottle and stopper, as shown.

BERNARD B. KLEBANOFF.
